UNITED STATES PATENT OFFICE.

MATILDA JANE SHUCK, OF BLOOMINGTON, ILLINOIS, ASSIGNOR OF ONE-HALF TO
PERRY L. NOGGLE, OF BLOOMINGTON, ILLINOIS.

BOTTLE-STOPPER.

Specification of Letters Patent. Patented June 29, 1915.

1,144,919.

Application filed February 12, 1914. Serial No. 818,405.

To all whom it may concern:

Be it known that I, MATILDA JANE SHUCK, a citizen of the United States, residing at Bloomington, in the county of McLean and State of Illinois, have invented certain new and useful Improvements in Bottle-Stoppers, of which the following is a specification.

This invention relates to bottle stoppers having for its primary object to provide a suitable stopper which is normally held in a closed position in the bottle neck to close communication therethrough.

A further object of the invention is to associate with the bottle a suitable elastic element which is fixedly engaged with the stopper so as to necessitate holding the stopper beyond the end of the bottle neck in order to dispense the contents of the bottle, the stopper automatically reengaging the neck as soon as pressure is released therefrom.

Other objects as well as the nature, characteristic features and scope of my invention will be more readily understood from the following description taken in connection with the accompanying drawings and pointed out in the claims forming a part of this specification.

Referring to the drawings: Figure 1 is a longitudinal sectional view of a bottle neck and a stopper constructed in accordance with my invention; Fig. 2 is a side elevation of my improved stopper showing its connection with the elastic element and in an outward position allowing the contents of the bottle to be dispensed; Fig. 3 is a bottom plan view of the elastic element used in the present invention, illustrating it in connection with a bottle stopper; and Fig. 4 is a sectional view taken on the line 4—4 of Fig. 1 and looking in the direction of the arrows.

In the drawings wherein is illustrated the preferred embodiment of this invention a bottle 5 is provided which may be of the ordinary or any desired form and has issuing from the upper end thereof the usual neck 6 which has formed on the terminal thereof a bead 7, said bottle being provided on the inner face adjacent the inner terminal of the neck 6, with an annular groove 8 which opens down into the body of the bottle as shown to advantage in Figs. 1 and 2.

Mounted in the bottle neck 6 is a stopper 9 which is preferably made of glass and has an annular flange 10 formed on its upper

peripheral edge which engages with the bead 7 when the stopper is in a closed position in the bottle neck. In order to prevent the breaking of the bottle stopper 9 or the neck 6 when the same contact an elastic band 11 is associated with the periphery of the stopper which engages with the inner periphery of the neck 6 when the stopper is in a closed position.

The stopper 9 is normally retained in a closed position in the bottle neck 6 as shown to advantage in Fig. 1 through the medium of an elastic element 12, the latter in the present instance comprising a resilient rod, one end of which tapers to a point as indicated at 13 and is provided with external screw threads which are engaged with internal screw threads on the interior of the stopper 9, the opposite end thereof being bifurcated and having the branches 14 thereof arcuated so as to normally lie in close proximity to the side of the bottle, the terminals 15 being beveled so as to snugly engage in the annular groove 8 thereby normally exerting pressure on the stopper 9. In order to fixedly engage the threaded shank of the elastic element 12 with the threaded recess of the stopper 9 a suitable adhesive material, such as glue, is applied to the shank and the recess of the stopper thereby preventing the unthreading of the stopper from the screw-threaded shank, it being necessary to rupture the threads on the bottle stopper in order to disengage the same from the bottle neck.

In Fig. 1 a conventional form of stopper retainer is provided as indicated at 14 which in the present instance merely comprises the usual wire strand clasp which engages around the bottle neck subjacent the bead 7 thereof and around the top of the stopper 9 so as to positively retain the stopper snugly in engagement with the bottle neck 6 and preventing its displacement during transportation or the like, a suitable trigger 15 being associated therewith in order to disengage the same from the bottle stopper when so desired.

In reduction to practice, we will assume that the branches of the bifurcation 14 have been engaged in the groove 8 of the bottle which is done by merely thrusting the branches through the bottle neck and allowing them to be engaged with the groove as soon as they have reached the desired point 110

- in the bottle neck, said branches engaging the sides of the bottle while passing therein in view of their resiliency which normally causes them to expand. When the contents of the bottle is to be dispensed, pressure is exerted on the stopper 9 so as to disengage the flange 10 from engagement with the bead 7 and causing the stopper to be unseated from the neck taking a position as advantageously illustrated in Fig. 2 in which position the elastic element 12 is under tension so as to automatically reengage the stopper in the bottle neck when pressure is released from the stopper.
- It will be understood that the above description and accompanying drawings comprehend only the general and preferred embodiment of this invention and that various minor changes in detail of construction, proportion and arrangement of the parts may be made within the scope of the appended claims and without sacrificing any of the advantages of my invention.
- Having thus fully described my invention, what I claim as new and desire to secure by Letters Patent is:—
1. A bottle stopper in combination with a bottle having a neck issuing therefrom, a stopper mounted in said neck and having

its outer terminal enlarged to provide an 30 annular flange to engage the free terminal of the bottle neck, and means for normally snugly engaging said flange with said neck including a rod, one end of which is threaded to facilitate engagement with said stopper and the opposite end formed to provide arms to engage the bottle, substantially as specified.

2. A bottle stopper in combination with a bottle having the usual neck and provided 40 with a groove adjacent the inner terminal of said neck, a stopper mounted in said neck, an elastic element comprising a resilient rod, one end of which is fixedly engaged with said stopper and the opposite end bifurcated 45 and having the free terminals of the branches thereof in engagement with said groove for normally holding said stopper snugly in engagement in the bottle neck and automatically reengaging said stopper in 50 said neck after it has been unseated therefrom.

In testimony whereof I affix my signature in presence of two witnesses:

MATILDA JANE SHUCK.
